UNITED STATES PATENT OFFICE

102,015

DESIGN FOR A TWIN SOCKET LIGHTING UNIT

George H. Weiner, Chicago, Ill.

Application August 24, 1936, Serial No. 64,546

Term of patent 14 years

To all whom it may concern:

Be it known that I, George H. Weiner, a citizen of the United States of America and a resident of Chicago, in the county of Cook and State of Illinois, have invented a new, original, and ornamental Design for a Twin Socket Lighting Unit, of which the following is a specification, reference being had to the accompanying drawing forming a part thereof, and in which:

Fig. 1 is a side elevational view of a twin socket lighting unit showing my new design;

Fig. 2 is also a side elevational view of the design shown in Fig. 1 but showing the same turned ninety degrees (90°) from the position in which it is shown in Fig. 1; and

Fig. 3 is an end elevational view thereof as seen from the bottom in Figs. 1 and 2.

I claim:

The ornamental design for a twin socket lighting unit, as shown.

GEORGE H. WEINER.
